DESCRIPTION

FIG. 1 illustrates a top perspective view of a light therapy gua sha device with base;

FIG. 2 illustrates an exploded top perspective view of the light therapy gua sha device with base;

FIG. 3 illustrates a top perspective view of a light therapy gua sha device of FIG. 2, shown separately from the base for ease of illustration;

FIG. 4 illustrates a front view of the light therapy gua sha device of FIG. 3;

FIG. 5 illustrates a back view of the light therapy gua sha device of FIG. 3;

FIG. 6 illustrates a left side view of the light therapy gua sha device of FIG. 3;

FIG. 7 illustrates a right side view of the light therapy gua sha device of FIG. 3;

FIG. 8 illustrates a top view of the light therapy gua sha device of FIG. 3;

FIG. 9 illustrates a bottom view of the light therapy gua sha device of FIG. 3;

FIG. 10 illustrates a back perspective view of the light therapy gua sha device of FIG. 3;

FIG. 11 illustrates a top perspective view of the Base of FIG. 2, shown separately from the light therapy gua sha device for ease of illustration;

FIG. 12 illustrates a front view of the base of FIG. 11;

FIG. 13 illustrates a back view of the base of FIG. 11;

FIG. 14 illustrates a left side view of the base of FIG. 11;

FIG. 15 illustrates a right side view of the base of FIG. 11;

FIG. 16 illustrates a top view of the base of FIG. 11;

FIG. 17 illustrates a bottom view of the base of FIG. 11; and,
